UNITED STATES PATENT OFFICE.

HERMAN F. NESLAGE AND HARRY H. WATSON, OF ST. LOUIS, MISSOURI.

TELEPHONE-WIRE HANGER.

SPECIFICATION forming part of Letters Patent No. 728,278, dated May 19, 1903.

Application filed July 14, 1902. Serial No. 115,529. (No model.)

To all whom it may concern:

Be it known that we, HERMAN F. NESLAGE and HARRY H. WATSON, citizens of the United States, residing at St. Louis, in the State of Missouri, have invented a new and useful Improvement in Telephone-Wire Hangers, of which the following is a specification.

Our invention relates to the hangers or brackets used for supporting overhead telephone-wires.

According to the present system of stringing overhead telephone-wires the messenger-wire, with the telephone-wire cable suspended therefrom by hooks, is supported on hangers or brackets fixed to the poles and the telephone-wire cable then pulled taut, the hooks in so doing sliding along the messenger-wire, which with the ordinarily-constructed hangers necessitates the displacement and readjustment by hand of the hooks that would otherwise be intercepted and stopped by the hangers, and so prevent the free hauling of the cable.

Our invention has for its object to provide a hanger or bracket by means of which the hooks adjacent thereto while hauling and tightening the telephone-wire cable are enabled to freely pass the hangers without the need of sending a man aloft to shift the hooks.

The invention consists in features of novelty, as hereinafter described and claimed, reference being had to the accompanying drawings, forming part of this specification, whereon—

Figure 1 is a front elevation of our improved telephone-wire hanger fixed to a pole, broken away, with the messenger-wire and telephone-wire cable suspended therefrom; Fig. 2, a cross-section through the wires on line 2 2 in Fig. 1, showing the hanger in side elevation; Fig. 3, a top plan of the same; Fig. 4, a cross-section through the hanger, broken away, on line 4 4 in Fig. 1; and Fig. 5, a cross-section through the messenger-wire on line 5 5 in Fig. 1, showing the end of the hanger-cap clamped thereto.

Like letters and numerals of reference denote like parts in all the figures.

a represents our improved telephone-wire hanger or bracket, which in this case is preferably L-shaped, but may be of any other suitable form, and fixed to the pole b by bolts

or screws in the usual manner. In the lower projecting part 1 of the hanger a is formed a bearing 2, which is preferably semicircular in cross-section and adapted to receive and support the messenger-wire c. The bearing 2 is provided with a correspondingly-shaped cap d, which is adapted to close over the messenger-wire c and is preferably formed with an inclined shank 3, having the base 4, which bears upon and is secured to the lower part 1 of the hanger a by a bolt 5, having the nut 5', which when screwed home against the under side of the hanger a closes the cap d upon the messenger-wire c and firmly holds it in its bearing 2. The cap d is formed for a suitable distance longitudinally from each end of the bearing 2 with an extended portion 6, having the same shape on its under side as the middle portion of the cap d and bearing therewith for the entire length of the cap d upon the messenger-wire c, or, if desired, the under side of the cap d may be longitudinally concave, as indicated by broken lines in Fig. 1, so as to bear at each end only upon the messenger-wire c. Each end of the cap d is formed, preferably, with two opposite lateral dependent ears or tags 7, which are made of thinner metal than the body of the cap d, whereby they are bent inward toward each other against the under part of the messenger-wire c and the latter thereby firmly gripped by the cap d, as seen particularly in Fig. 5.

From the cap d on its front side or edge preferably depends a lug 8, which when the cap d is placed in position over the bearing 2 engages in a notch 9, formed vertically in the corresponding side of the bearing 2, and thereby locks and prevents any end movement or displacement of the cap d when the telephone-wire cable is hauled along the messenger-wire c, as hereinafter more particularly referred to.

The cap d is curved or tapered externally from its maximum thickness in the middle to its minimum thickness at each end, which is adapted to closely hug the messenger-wire c. Furthermore, the cap d is formed externally and longitudinally at the top with a convex or tapered rib or enlargement 10, which extends from nothing at each end of the cap d to its maximum height at the mid-

dle of the latter, each end of the cap *d* and rib 10 presenting practically a continuous surface with the upper surface of the messenger-wire *c*.

5 *e* represents the lead tube containing the telephone-wires 11, which, with the tube *e*, are herein termed the "telephone-wire cable," and to the tube *e* are clamped the hooks *f*, which are hooked onto the messenger-wire *c* 10 in the usual well-known manner, and it is here noted that the lower part 1 of the hanger *a*, at and adjacent to the bearing 2, combined with the cap *d*, is so shaped as to offer no obstruction to the hooks *f* when passing the 15 hanger *a*, as hereinafter more particularly referred to.

In operation the messenger-wire *c* being first strung along the entire route and held taut in the bearings 2 of the hangers *a* by the 20 caps *d*, the hooks *f*, carrying the telephone-wire cable, are then hooked onto the messenger-wire *c*, the cable at this stage having more or less sag between the successive poles *b*. The telephone-wire cable is then hauled tight 25 in the usual manner, and in so doing the hooks *f* slide along the messenger-wire *c*, those hooks *f* which would otherwise be

stopped by the ordinary hangers riding over the convex caps *d* of the hangers *a*, as indicated by broken lines in Fig. 1, and clearing 30 themselves therefrom as the hauling of the telephone-wire cable proceeds, thereby obviating the necessity of a man climbing each pole *b* to remove and replace the hooks *f*.

What we claim as our invention, and desire 35 to secure by Letters Patent, is—

In a telephone-wire hanger having a bearing for the messenger-wire, a cap to the said bearing and wire, the said cap extending beyond each end of the bearing and having its 40 top longitudinally convex, ears depending from each end of the cap, a lug dependent from the cap and entering a slot in the hanger, and additional means for fixing the cap to the hanger, substantially as described. 45

In testimony whereof we have signed our names to this specification in the presence of two subscribing witnesses.

HERMAN F. NESLAGE.
HARRY H. WATSON.
